ARTHUR L. RUSSELL, OF HYDE PARK, MASSACHUSETTS, ASSIGNOR TO UNITED SHOE MACHINERY COMPANY, OF PATERSON, NEW JERSEY, A CORPORATION OF NEW JERSEY.

END-LASTING MECHANISM.

1,080,235.

Specification of Letters Patent.

Patented Dec. 2, 1913.

Application filed July 11, 1910. Serial No. 571,359.

To all whom it may concern:

Be it known that I, ARTHUR L. RUSSELL, a citizen of the United States, residing at Hyde Park, in the county of Norfolk and 5 State of Massachusetts, have invented certain Improvements in End-Lasting Mechanisms, of which the following description, in connection with the accompanying drawings, is a specification, like reference characters on the drawings indicating like parts in the several figures.

This invention relates to lasting machines and particularly to end lasting mechanisms.

It has for an object to improve the actuating mechanism for end embracing wipers and more especially to provide actuating mechanism by which an operator is given greater control of the position and movement of the wipers than has heretofore existed.

A very important feature of this invention is found in actuating mechanism by which one member of end embracing wipers may be moved relatively to or differently 25 from another. It often occurs that the wipers do not exactly fit the shoe, particularly if the shoe is made on a crooked last or a last very commonly in use, the outer and inner sides of the toe of which are of different shape. It also frequently happens 30 that a shoe is not so accurately centered between the wipers that the wipers on the two sides come over the last bottom to equal bearing with relation to the lip or shoulder 35 of the innersole. Sometimes this is a result of the innersole being channeled in farther on one side than on the other side of the toe. These considerations and others render it desirable that the operator be able to 40 give to one wiper additional movement or movement different from or independent of the movement which the other wiper is given, or that he be able to adjust the wipers on the two sides of the toe end relatively 45 to one another to fit or adapt the wipers to the particular work being done. I have here mentioned the conditions prevailing at the toe end of the shoe which call for the use of this invention and have herein illustrated the invention as embodied in toe lasting mechanism. Somewhat similar conditions to certain of those mentioned are also 50 sometimes found at the heel of the shoe for the heel portions of lasts are often unsymmetrical. There is found particular diffi-

culty in properly wiping into snugly lasted position the upper at the inner side of certain shapes of lasts at and adjacent to the breast of the heel or the end of the heel stiffener.

The application of this invention to heel lasting wipers to enable the wiper acting on the inner side of a right or a left shoe to be adjusted up to the inner side of the heel portion of the last or to be moved inwardly over the last farther than the opposed wiper is moved will be obvious and requires no illustration.

It is a characteristic of the illustrated embodiment of this invention that either wiper may be advanced or retracted while the other wiper remains substantially stationary or is reversely moved. If desired, either wiper may be so moved repeatedly with relation to the other wiper for overworking a stubborn or difficult portion of the shoe. In the construction herein shown by way of example to assist in the explanation of the invention the wipers and their supporting and guiding means, including the cam 80 grooves in the wiper carriers for controlling the direction of the wiper closing movement, may be similar to a well known construction. Each wiper is connected with one member of a split plunger which terminates in a rack 85 bar. Between the rack bars is a pinion pivoted on a swinging lever by which the plunger members are actuated together to impart like movements to the wipers. A second lever or lever arm is mounted to 90 turn in the swinging lever and has a worm connection with the pinion by which the latter can be turned to move the rack bars, plunger members and wipers relatively. The turning lever arm is furnished with 95 the handle by which the swinging lever is operated so that the operator can, with the single hand which he is accustomed to using for actuating the wipers, advance the wipers and also adjust or relatively move them as 100 the shape of the last or the condition of the work may require. By rotating the lever arm while advancing it he can accelerate the movement of one wiper and retard that of the other and by rotating the hand lever 105 while slowly advancing it he can advance one wiper while holding the other one substantially stationary. By suitable manipulation one wiper may be repeatedly advanced and retracted while the other re- 110

mains substantially at rest and holds the upper in overworked position under it. A friction lock controlled by a thumb piece adjacent to the handle of the lever arm provides means for holding the mechanism as a whole while the lever arm is turned to advance and retract the wiper plates alternately.

The features above disclosed and other 10 features of this invention, including certain combinations of parts and details of construction, will be understood from the following description of the illustrated exemplification of the invention and will be 15 pointed out in the claims.

Figure 1 is a plan view of the toe lasting mechanism of a bed lasting machine equipped with this invention and showing in full and broken lines two positions of a shoe, 20 or a right and a left last, to which the end embracing wipers are capable of being adjusted; Fig. 2 is a perspective view.

The wipers are plates 2, detachably connected with wiper holders 4 by clamps 5 supported in a lasting head 6 of known construction which is rotatable in a support 8 about a horizontal axis extending longitudinally of the machine. The wiper holders have cam slots 10 to receive roller studs 25 which project from the head and direct movement of the wipers inwardly as they are advanced so that the plates are closed together by like normal movements over the opposite sides of the end portion of the shoe. 30 The wiper holders are each connected by links 12 with one member 14 of a split plunger, the rear end of each member being formed as a rack bar in engagement with a pinion 15 located between the two bars. A 35 lever 20 is connected by a link 21 to a fulcrum on the support 8 and receives loosely the shaft of the pinion 15. Swinging movement of lever 20 on its fulcrum thus acts 40 through the described connections to give like normal movements to the wipers. The lever 20 has bearings 24 in which is rotatable a lever arm 25 provided with the handle portion by which the lever 20 is to be swung. The rotatable arm 25 has a worm on its inner 45 end which is in engagement with a toothed segment 28 fast on the shaft of the pinion 15. This connection enables the pinion to be turned at any time, to move the wipers relatively through the members and 50 by that hand of the workman which is employed in swinging the operating lever 20 of the divided plunger. The lever 20 pivotally supports a friction pawl 30 which is spring 55 pressed toward locking engagement with a curved bar 32 that extends from the support 8. A thumb piece 34 extends into position to be engaged for releasing the pawl by the operator's hand which is manipulating the lever arm 25.

60 The nature of the invention has been fully

explained and its purposes and possible uses have been outlined with sufficient detail to enable others to employ it in an end lasting mechanism of any suitable type adapted for use at the toe or the heel of a shoe.

70

I claim as new and desire to secure by Letters Patent of the United States:

1. An end lasting mechanism comprising coöperating wiper plates, means for actuating said plates over the shoe bottom together 75 to do their work, and connections from said first mentioned means for imparting supplemental relative movements to the wiper plates.

2. An end lasting mechanism comprising 80 coöperating wiper plates arranged to embrace an end portion of a shoe, means for simultaneously advancing and closing said plates, and connections from said first mentioned means for further closing one of said 85 plates alone.

3. An end lasting mechanism comprising opposed coöperating wiper plates, means for simultaneously advancing and closing said plates together, and an additional means 90 connected with the opposed wiper plates for moving one of said plates inwardly and the other outwardly.

4. An end lasting mechanism comprising opposed coöperating wiper plates, means for 95 operating said plates together over the last, and one means connected with the opposed wiper plates for further moving one plate over the last and reversely moving the other plate.

5. An end lasting mechanism comprising coöperating wiper plates, means for operating said plates together over the last, and additional means operatively connected with the first mentioned means for further moving 105 one plate without similarly moving the other plate.

6. An end lasting mechanism comprising coöperating wiper plates, means acting through one train of connections for operating said plates together over the last, said mechanism having provision for further moving one plate alone by the same operating means to wipe the stock inwardly over the less full side of the last.

110 7. An end lasting mechanism comprising coöperating wiper plates, and operating means comprising an actuator connected with both plates and by one movement of which said plates may be moved alike or 120 by a different movement of which the plates may be moved reversely relatively to one another.

8. An end lasting mechanism comprising coöperating wiper plates, and one operating 125 means having relatively movable connections with the two wiper plates and by which both said plates may be advanced and closed alike or by a dissimilar actuation of said operating means one of said 130

- plates may be moved differently from the other.
9. An end lasting mechanism comprising coöperating wiper plates, means to advance and close said plates over the end portion of a shoe including one operating device by which said plates may be adjusted relatively to fit the last and may then be moved together to do their work.
10. An end lasting mechanism comprising coöperating wiper plates adapted to advance and close over the end portion of a shoe and a single operating means by which said plates may be actuated to wipe the upper over the two sides of the shoe and may then be moved relatively for pressing the upper farther inwardly on one side at a time.
11. A lasting mechanism comprising end lasting wipers, means for supporting and guiding said wipers to advance and close over the work, a divided plunger the members of which are each connected to a wiper, and means for actuating said plunger as a whole to impart normal working movements to the wipers, said mechanism having provision for imparting separate movements to each member of said plunger and the wiper connected to said member.
12. A lasting mechanism comprising end lasting wipers, means for supporting and guiding said wipers to advance and close over the work, and one operating means constructed and arranged to impart to said wipers like movements or, at the will of the workman, to one wiper a different movement from that imparted to the other wiper.
13. A lasting mechanism comprising end lasting wipers, means for supporting and guiding said wipers to advance and close over the work, a swinging lever connected to said wipers to move them together and adapted for rotatory movement to impart a different movement to one wiper from that imparted to the other wiper.
14. A lasting mechanism comprising end lasting wipers, means for supporting and guiding said wipers to advance and close over the work, a rack bar connected to each wiper, a pinion connecting the bars, means to move the pinion and rack bars together to actuate the wipers, and means to turn the pinion to adjust the wipers relatively.
15. A lasting mechanism comprising end lasting wipers, means for supporting and guiding said wipers to advance and close over the work, a rack bar connected to each wiper, a pinion connecting the bars, and a single operating means adapted for one movement to actuate the wipers together and for a different movement to turn the pinion for relatively actuating the wipers for the purpose described.
16. A lasting mechanism comprising end lasting wipers, means for supporting and
- guiding said wipers to advance and close over the work, and a single operating member adapted for one movement to actuate the wipers together and for a different movement to move them relatively for the purpose described.
17. An end lasting mechanism comprising end embracing wipers and an actuating mechanism having a hand lever for imparting working movements to the wipers together and which hand lever is capable of manipulation to advance a wiper on one side of the shoe more than the wiper on the other side.
18. An end lasting mechanism comprising end embracing wipers and one actuating mechanism connected with both wipers for imparting working movements to the wipers and which is capable of a different manipulation for advancing unyieldingly a wiper on a selected side of the shoe end farther than the opposed wiper on the opposite side.
19. An end lasting mechanism comprising end embracing wipers and actuating mechanism comprising a lever for imparting working movements to the wipers and which is capable of manipulation to move the wipers differentially to adjust them for right and left lasts.
20. An end lasting mechanism comprising end embracing wipers and actuating mechanism for imparting working movements to the wipers, said actuating mechanism comprising an operating member through manipulation of which said working movements are effected and which has capacity for moving the wipers differentially prior to their engagement with the work to enable them to fit shoes the opposite sides of the ends of which present different contours or inclinations to the respective wipers.
21. An end lasting mechanism comprising end embracing wipers and actuating mechanism for imparting working movements to the wipers, comprising suitable connections and a lever arm which can be swung to advance the wipers together and can be rotated on its longitudinal axis to adjust the wipers relatively.
22. An end lasting mechanism comprising end embracing wipers and actuating mechanism for imparting working movements to the wipers, said actuating mechanism comprising an operating lever which can be swung to move the wipers together and can be rotated on its own longitudinal axis to move the wipers differentially.
23. An end lasting mechanism comprising end embracing wipers, and one actuating mechanism having a hand lever for imparting working movements to the wipers, said actuating mechanism having provision for permitting the operator, by means of said hand lever and during the working

movements of the wipers to make relative adjustments of the wipers at the two sides of the shoe end.

24. An end lasting mechanism comprising 5 end embracing wipers and actuating mechanism therefor comprising supporting and guiding means for the wipers coöperating with cam faces thereon, and an actuator having separate connections with the wipers 10 adapted to actuate them together and also to actuate one wiper differently from the other.

25. An end lasting mechanism comprising 15 end embracing wipers and actuating mechanism therefor comprising supporting and guiding means for the wipers coöperating with cam faces thereon, and actuating means comprising a member capable of movement to actuate the wipers alike and a second 20 member through which the first actuation is imparted and which is capable of another movement to actuate one wiper differently from the other wiper.

26. An end lasting mechanism comprising 25 end embracing wipers and an actuating mechanism therefor having a single controlling means constructed and arranged for manipulation to close the wipers equally from opposite sides of the shoe end or to 30 close the wipers unequally at the will of the operator.

27. An end lasting mechanism comprising 35 end embracing wipers, a support on which they can slide and turn to do their work and actuating mechanism for the wipers having a single controlling means and constructed and arranged to advance and turn the wipers together both toward the median line of the shoe or to turn them upon said support both toward the right or the left of the median line of the shoe.

28. An end lasting mechanism comprising 40 end embracing wipers and one actuating mechanism therefor constructed and arranged to turn the wipers together both toward the median line of the shoe and also capable of manipulation to hold one wiper

substantially stationary while turning the other wiper farther toward the median line of the shoe.

50

29. An end lasting mechanism comprising 55 end embracing wipers and one actuating mechanism therefor adapted to advance or retract either wiper differentially from the other at the will of the operator.

55

30. An end lasting mechanism comprising 60 end embracing wipers and one actuating mechanism therefor adapted to advance and retract repeatedly either wiper without imparting a corresponding movement to the other.

31. An end lasting mechanism comprising 65 end embracing wipers, and an actuating member which is mounted to turn about different axes and is connected with the wipers 70 at opposite sides of the shoe end to move said wipers alike by said turning movements about one axis or differently from one another by turning movements about another axis.

70

32. An end lasting mechanism comprising 75 end embracing wipers, and actuating means comprising a wiper advancing and retracting lever by manipulation of which, during the operation of the wipers, the movement 80 of the wiper member at either side of the shoe end selected by the operator can be accelerated relatively to the movement of the other wiper member.

80

33. An end lasting mechanism comprising 85 end embracing wipers, and an actuating mechanism by manipulation of which both wipers can be advanced together or one wiper member can be advanced farther over the last bottom at the option of the workman after the wiper member at the other side of the shoe end has been arrested.

85

In testimony whereof I have signed my name to this specification in the presence of two subscribing witnesses.

ARTHUR L. RUSSELL.
